US00D764513S

(12) **United States Design Patent**
Kim et al.

(10) **Patent No.:** **US D764,513 S**
(45) **Date of Patent:** **** Aug. 23, 2016**

(54) **DISPLAY SCREEN OR PORTION THEREOF
WITH GRAPHICAL USER INTERFACE**

(71) Applicant: **Samsung Electronics Co., Ltd.,**
Suwon-si (KR)

(72) Inventors: **Youngrim Kim, Seoul (KR); June-Seok
Kim, Seoul (KR); Jihyun Lee, Seoul
(KR); Minkyung Cho, Seoul (KR)**

(73) Assignee: **SAMSUNG ELECTRONICS CO.,
LTD., Suwon-Si (KR)**

(**) Term: **15 Years**

(21) Appl. No.: **29/529,083**

(22) Filed: **Jun. 3, 2015**

(30) **Foreign Application Priority Data**

Feb. 27, 2015 (KR) 30-2015-0010382

(57) **CLAIM**

The ornamental design for a display screen or portion thereof with graphical user interface, as shown and described.

DESCRIPTION

The FIGURE is a front view of a display screen or portion thereof with graphical user interface showing our new design. The outermost broken lines show a display screen or portion thereof and form no part of the claimed design. The broken lines showing portions of the graphical user interface form no part of the claimed design.
